UNITED STATES PATENT OFFICE.

CHARLES W. STEVENS, OF NEW YORK, N. Y.

SHOULDER-BRACE AND SUSPENDERS.

SPECIFICATION forming part of Letters Patent No. 251,805, dated January 3, 1882.

Application filed November 18, 1881. (No model.)

To all whom it may concern:

Be it known that I, CHARLES W. STEVENS, a resident of the city, county, and State of New York, have invented certain new and useful Improvements in Shoulder-Braces and Suspenders; and I do hereby declare that the following is a full, clear, and exact description thereof, reference being had to the accompanying drawings, and to the letters of reference marked thereon, making a part of this specification.

This invention relates to the manufacture of shoulder and back bracing suspenders. It has for its object a perfect bracing of the shoulders, admitting of adjustment to a greater or less degree of tension without undue strain upon the pantaloons or waistband, and with entire relief from all strain when the wearer is seated.

In the accompanying drawings, Figure 1 is a perspective view of my invention; Fig. 2, a detached view, illustrating the combination of a stiffening-piece with the brace; Fig. 3, a front elevation in detail, and Fig. 4 a similar view of the reverse side of a device for adjusting the length of the suspender-cords. Fig. 5 is a view of the same with the outer plate removed, exhibiting the inner pivoted catch. Figs. 6 and 8 illustrate the forms of the blanks from which the device is formed; and Fig. 7 is a longitudinal section in line xx of Fig. 4, illustrating the construction of the inner catch.

A A are shoulder-straps, each formed of a piece of webbing, fitted to pass from a point on the back of the wearer, below the shoulder-blade up over the shoulder, and thence down under the arm, back upon itself, so as to form in effect a loop, fitting over the shoulder. This loop may be enlarged or reduced by means of a buckle, A'.

The back-pieces of the two shoulder straps or loops are stiffened by a lining-piece, B, Fig. 2, of thin metal, hard rubber, or other suitable material, and are furnished each with eyelets or loops along the edge thereof, or preferably with friction-pulleys C C as an equivalent therefor. They are drawn together more or less, as desired, to brace back and support the shoulders, by means of suspender-cords D D. These suspender-cords are led through the eyes in the brace-bands, or through the pulleys C C, so as to lace and draw the two bands together,

as shown in Fig. 1, and are thence carried through loops ll , stitched to the shoulder-pieces over each shoulder, and down to the front buttons of the pantaloons. The rear ends of these cords are made to button upon the rear buttons of the pantaloons. The stiffening-piece B serves to prevent the webbing from doubling up, to equalize the tension of the interlaced cords upon the brace, and to prevent the brace or loop from pinching the shoulders in passing around the same.

The pulleys C C are cheaply made by bending over a sheet-metal strip to embrace the sheave. The two projecting ends of the strip serve to embrace between them the shoulder-strap and its stiffening-plate, and are readily secured thereto by rivets passing through the whole from side to side. Side straps, H H, also made of webbing, are united to the lower end of the shoulder-straps A A in the rear, to extend thence diagonally toward the front, and are provided with loops hh to engage the hip-buttons of the pantaloons. These loops hh are preferably connected to the side straps by means of slides, buckles, or other devices admitting of their adjustment in length.

The rear loops of the suspender-cords D D are formed by bending the cord upon itself and securing the end by a metal clasp, in the usual manner. The cords D are made adjustable, and are lengthened or shortened at pleasure by passing the end of the cord down and back through a tubular clapping device, K. The device consists mainly of a sheet-metal blank, Fig. 6, whose projecting ends are bent over to form tubular ways, as shown in Fig. 5.

A simple double catch, L, formed by bending up, as shown in Fig. 7, the ends of a metal blank, Fig. 8, is pivoted centrally within the device between the two folds or lengths of the cord, (see dotted lines, Figs. 3 and 4,) and serves to engage it and prevent its accidental slipping. In turning upon its pivot the opposite lateral edges, ww , of the two bent-up ends of the plate operate to force the cord out into the opening tt left in the ways on either side, as shown in Fig. 5. This catch is operated to cause it to engage the cord by means of an outer swinging plate, M, arranged to turn upon the pivot of the catch, and to which its two

extreme ends are secured by lugs projecting therefrom through apertures in the swinging plate M. (See Fig. 7.)

The outer swinging plate, M, extends beyond the tubular plate confining the cords, and its upper edge is bent over and pierced to allow the two ends of the cord to be led through it, so that when tension is exerted on the cord it will have a tendency to turn the plate M, and with it the catch L, so as to cause it to force the cord outward (see Fig. 3) into the opening t, as described, and thus securely hold it and prevent its slipping. When the cord is released from tension the plate and catch may be readily turned in the opposite direction, leaving the cord free to run easily through in either direction. The cross-lacing of the suspender-cords through the shoulder-straps tends powerfully to draw these straps together when a person wearing them stands up, the degree of tension upon the shoulders and shoulder-blades of the wearer being determined measurably by the length of the suspender-cords. So soon, however, as the person sits down the tension is instantly relaxed.

I contemplate, as a modification of my improved brace, causing the suspender-cords to terminate at the lower end of the stiffening plates in the shoulder-straps, the ends being secured thereto by any suitable device, in which case the shoulder-straps themselves are extended down to button upon the rear button of the pantaloons. The tension upon the suspender-cords in such case is wholly from the front.

What I claim as new, and desire to secure by Letters Patent, is—

1. A shoulder-brace constructed of independent shoulder straps or loops A A, drawn together at the back by interlaced adjustable suspender-cords D D, led over the shoulders and adapted to be secured to a waistband, substantially in the manner and for the purpose herein set forth. 40

2. The combination, with the independent shoulder-straps A A, constituting a shoulder-brace, and interlacing cords D D, adjusted to draw them together, of stiffening-plates B B, serving to equalize the tension upon the brace-straps, substantially as and for the purpose 50 herein set forth.

3. The combination, with the shoulder-straps A A, stiffening-plates B B, and tension suspender-cords D D, of a series of pulleys, C C, through which the cords are led to interlace 55 and draw together the shoulder-straps, substantially as and for the purpose herein set forth.

4. In combination with the end of the suspender and tension cords D D of the shoulder-braces A A, the tubular retaining device K, provided with a pivoted catch-plate, L, actuated by a swinging outer plate, M, through which the cord is led, substantially in the manner and for the purpose herein set forth. 60

In testimony whereof I have signed my name to this specification in the presence of two subscribing witnesses.

CHARLES W. STEVENS.
